UNITED STATES PATENT OFFICE.

JAMES S. TAYLOR, OF DANBURY, CONNECTICUT; EUGENE M. BULKLEY
EXECUTOR OF SAID TAYLOR, DECEASED.

HAT-FELTING MACHINE.

SPECIFICATION forming part of Letters Patent No. 712,466, dated October 28, 1902.

Application filed February 7, 1902. Serial No. 93,019. (No model.)

To all whom it may concern:

Be it known that I, JAMES S. TAYLOR, a citizen of the United States, residing at Danbury, county of Fairfield, State of Connecticut, have 5 invented a new and useful Hat-Felting Machine, of which the following is a specification.

My invention relates to felting-machines generally, more especially to machines for 10 felting hat-bodies, and has for its object to so improve the construction of the machine that while adapted to the felting of both soft and stiff hats indiscriminately it shall be especially adapted to the felting of soft or rough- 15 rider hats, the special objects being to increase the capacity of the machine, to improve the quality of the work performed, and to make the machine easy to operate and attractive by its general mode of operation to 20 the operator.

With these ends in view I have devised the novel felting-machine which I will now describe, referring to the accompanying drawings, forming part of this specification, and 25 using reference characters to designate the several parts.

Figure 1 is an end elevation of my novel felting-machine as in use, a bundle of hat-bodies being shown in the felting-chamber 30 between the rollers; and Fig. 2 is a similar view, the upper roller being raised, as when the operator is rerolling a bundle of hat-bodies.

It is well understood by those familiar with 35 the art of felting hat-bodies that the best effect in the first portion of the felting operation is produced by what is called the "dead-fall" action of the top or worker roller—that is, the simple action of gravity of the worker- 40 roller and the frame by which it is carried unassisted by springs or weights—and that the pressure exerted upon the roll of hat-bodies must be increased as the felting operation proceeds. This action of increasing 45 the pressure upon the roll of hat-bodies requires the best of judgment on the part of the operator in applying the proper degree of pressure at the different stages of the felting operation. This additional pressure or force 50 applied by the workmen is quite properly termed "nerve force," and long practice has

demonstrated that it can be very much better applied by hand-power than by foot-power.

In felting a roll of hat-bodies they require to be changed—that is, the bundle must be 55 taken out of the machine, opened, and re-rolled after from ten to twenty seconds' action of the machine, which, with machines as ordinarily constructed is hard work and very 60 exhausting.

By my novel machine I aim to increase the capacity of the machine and at the same time to improve the quality of the work performed by reducing to the minimum the amount of strength required to be used by the operator 65 and so organizing the machine that but little movement is required by the operator and that movement is made very easy, so that the operator not being physically exhausted may 70 apply the "nerve force," so called, that is required to obtain the best results in the felting operation in the easiest manner possible and without serious physical labor.

10 denotes a frame, which may be of any ordinary or preferred construction; 11, the 75 front roller, shown as journaled on the frame; 12, the back roller, journaled on standards 13, (one only being shown,) extending upward from the frame, and 14 the top or worker roller, which is journaled on a yoke or frame 80 15, which is pivoted concentrically with the back roller—that is to say, the yoke or frame is adapted to swing concentrically with the axis of rotation of the back roller. It is 85 wholly immaterial how the machine is driven or how power is transmitted to the rollers. I have indicated by dotted lines a belt-pulley 16 on the shaft of the front roller, sprocket-wheels 17 on the shafts of all the rollers, and 90 a sprocket-chain 18, connecting the sprocket-wheels.

19 denotes a hand-lever pivoted to a lug 20 upon the frame. This hand-lever is shown as connected by a link 21 to a lever 22, pivoted on one of the standards 13 above the 95 shaft of the back roller. This lever extends backward from its pivotal point, and a spring 23 connects it with a convenient portion of the frame, the connection of the spring with the lever being preferably adjustable, as 100 shown, so as to enable the operator to adjust the tension of the spring on the lever. The

action of the spring is to lift the swinging frame and worker-roller when the hand-lever is released, as presently described.

24 denotes a lug on the frame, which extends 5 into position to be engaged by lever 22 when it is desired to lift the frame and the worker-roller, as clearly shown in Fig. 2. The hand-lever is preferably provided with a plate 25, (see dotted lines,) which is adapted to engage 10 a rack 26 to lock the hand-lever at its lowered position as in use. (See Fig. 1.)

The operation of my novel machine in felting a bundle of hat-bodies will be readily understood from the drawings. To lift the frame 15 and the worker-roller, as in inserting or removing a bundle of hat-bodies, the operator disengages the hand-lever from the rack, and the spring 23 at once acts through the lever 22 to raise the hand-lever and through the 20 engagement of lever 22 with the lug upon the frame by which the worker-roller is carried raises the frame and with it the worker-roller. The hand-lever is locked at the raised position by engaging the lever with the rack, as shown 25 in Fig. 2. As soon as a bundle of hat-bodies has been placed in the felting-chamber between the rollers the operator lowers the hand-levers and locks it in the lowered position, as in Fig. 1, which permits the full effect of the 30 "dead-fall" action, so called, of the worker-roller upon the bundle of hat-bodies, the spring having no action on the yoke and worker-roller when the hand-lever is in its lower position. As the felting operation proceeds and it be- 35 comes necessary to apply additional pressure to the worker-roller it will be noted that both hands and both feet of the operator are free—that is, the operator is not required to have his foot upon a treadle or foot-lever or his 40 hand upon a hand-lever—so that with his hand he may apply any required amount of pressure—*i. e.*, nerve force—to the frame which carries the worker-roller, and thus regulate to the finest degree the additional pressure 45 sure that it is desirable to apply to the bundle of hat-bodies through the worker-roller.

Having thus described my invention, I claim—

1. In a machine of the character described 50 the combination with front and back rollers, a worker-roller and a swinging frame by which

the worker-roller is carried, of a lever 22 movable independently of and adapted to engage the swinging frame, a hand-lever and a link connecting the hand-lever and lever 22, where- 55 by when the hand-lever is raised lever 22 will be raised also and will engage and raise the swinging frame and worker-roller.

2. In a machine of the character described the combination with a frame, front and back 60 rollers, a worker-roller and a swinging frame by which the worker-roller is carried, of a lever 22 movable independently of and adapted to engage the swinging frame, a spring connecting the rear end of said lever with the 65 frame, a hand-lever and a link connecting the forward end of lever 22 with the hand-lever, said spring acting when the hand-lever is raised into engagement with the swinging frame to partly counterbalance the weight of 70 the swinging frame and roller.

3. In a machine of the character described the combination with front and back rollers, a hand-lever, a lever 22 and a link connecting said hand-lever with lever 22, of a worker- 75 roller and a swinging frame by which said worker-roller is carried and which is movable independently of the lever 22, said swinging frame being provided with a lug adapted to be engaged by lever 22, so that when the 80 hand-lever and lever 22 are raised the swinging frame will be picked up and the worker-roller raised.

4. In a machine of the character described the combination with front and back rollers, 85 a worker-roller and a swinging frame by which the worker-roller is carried, of a hand-lever, a lever 22 movable independently of and adapted to engage the swinging frame, a link connecting the hand-lever and lever 22 and 90 means for locking the hand-lever in a raised or lowered position, so that the swinging frame and the worker-roller may be left free or may be moved out of operative position by manipulation of the hand-lever. 95

In testimony whereof I affix my signature in presence of two witnesses.

JAMES S. TAYLOR.
